ABSTRACT

Method and apparatus for attaching a dispenser cathode to a support structure is disclosed. The dispenser cathode body includes a peripherally directed groove into which the end of a tubular support structure is crimped. A retaining wire is forced into the groove containing the crimped end of the support to produce an interference fit between the retaining wire, support structure and the cathode body.

**APPARATUS FOR ATTACHING A DISPENSER CATHODE
TO A SUPPORT**

DESCRIPTION OF THE PRIOR ART

Heretofore, dispenser cathode bodies have been attached to tubular support structures by means of crimping the end of the tubular support against the outer periphery of the cathode body or against a retaining ring carried in a groove around the periphery of the cathode body. The problem with merely crimping the end of the cathode tubular support structure against the cathode body is that repeated thermal cycling of the cathode and its support structure, as encountered in use, produces a mechanical working of the crimped end of the tube relative to the cathode body which results in producing a loose connection between the cathode body and the support structure. This loose connection impedes the flow of cathode current and causes the beam to have substantial noise superimposed thereon in use. In the case where the cathode support structure is welded, as by spot welding, to a ring carried within a groove in the cathode body, the mechanical working causes the welded points to break loose causing the beam current to be diverted to the remaining welds which overtaxes these welds and causes them to burn out. As a result, the tube becomes noisy and leads to cathode failure.

SUMMARY OF THE PRESENT INVENTION

The principal object of the present invention is the provision of an improved method and apparatus for attaching a dispenser cathode to a cathode support structure.

One feature of the present invention is the provision of a groove around the periphery of a dispenser cathode body into which a portion of the tubular cathode support structure is crimped and including the provision of a retaining wire wedged into the groove to produce a tight interference fit between the wire, the support structure and the cathode body.

Another feature of the present invention is the same as the preceding feature wherein the retaining wire is connected together at its ends to form a retaining ring.

Other features and advantages of the present invention will become apparent upon a perusal of the following specification taken in connection with the accompanying drawing which is a longitudinal view, partly in section, depicting a dispenser cathode attached to its support structure and incorporating features of the present invention.

DESCRIPTION OF THE PREFERRED EMBODIMENTS

Referring now to the drawing, there is shown a dispenser cathode 1 attached to its support structure 2 and incorporating features of the present invention. More particularly, the cathode emitter 1 includes a cylindrical cathode emitter body 3, as of impregnated tungsten or thoriated tungsten. In a preferred embodiment the cathode emitter body 3 is a porous tungsten body with the bores being impregnated with cathode emitter material such as barium oxide, barium strontium aluminate or barium strontium tungstate. The cathode emitter body 3 includes a spherically concave cathode emitting surface from which the electrons are emitted to produce a beam of electrons for use in an electron beam tube.

A groove 4 is provided around the periphery of the cathode

60

body 3. Cathode emitter body 3 is carried from the end of a tubular cathode support member 2, as of 0.003 to 0.005 inch thick tantalum tubing. The support end of the tubing 2 is crimped around the marginal lip 5 of the cathode body 3 with the end portion of the tubular support 2 being crimped into the groove 4.

A retaining wire 6, as of 0.030-inch diameter tantalum, is wedged into the groove 4 to produce a tight interference fit between the retaining wire 6, the end of the support tube 2, 10 and the cathode body 3. The two ends of the retaining wire 6 are spotwelded together at 7 to form a retaining ring structure tightly wedged into the groove 4.

The heating structure, not shown, is positioned inside the tubular support structure 2 at the back side of the emitter body 3 for heating the emitter body 3 to operating temperature, as of 1,100°C.

In a typical example, the emitter body 3 is made of porous tungsten with the pores infiltrated with cathode emitter material to form a dispenser cathode. The cathode has a diameter of 1.165 inches and a minimum thickness, on its axis of revolution, of 0.125 inch. The cathode draws between 5 and 10 amps of cathode beam current, in use.

The advantage of the cathode and its method of attachment, as shown in the drawing, is that electrical connection between 25 the tubular support structure 2 and the cathode body 2 is made through the tight mechanical interference fit which is maintained due to the provision of the retaining ring 6. These mechanical connections do not work loose with continued thermal cycling of the cathode such that the operating life and 30 the noise figure for the beam are substantially improved over prior art methods of attaching the cathode bodies to the support structures.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

40 1. In a dispenser cathode emitter structure, means forming a dispenser cathode emitter body, means forming a tubular support structure for supporting said cathode emitter body, means for attaching said support structure to said cathode emitter body, the improvement wherein, said cathode emitter body includes a groove extending around the periphery of said emitter body, said attaching means including a portion of said tubular support structure extending radially into said groove, and a retaining wire structure in said groove, said retaining wire structure being dimensioned to provide, together with 45 said portion of said support structure, an interference fit in said groove for fixedly attaching said cathode emitter body to said support structure.

2. The apparatus of claim 1 wherein an end portion of said tubular support structure extends into said groove.

55 3. The apparatus of claim 2 wherein said dispenser cathode body includes a porous tungsten body having the pores thereof infiltrated with an emitter material.

4. The apparatus of claim 2 wherein said retaining wire is an unbroken retaining ring.
